PRESSURE ROLLER

Charles E. Reed, Chicago, Ill.

Application March 10, 1937, Serial No. 130,183

8 Claims. (Cl. 271—51)

My invention relates to the printing and feeding rollers in rotary printing presses, and more particularly to the rollers associated therewith and commonly called pressure rollers, the function of these being to hold the web or sheet in proper contact for printing or feeding purposes.

One object of my invention is to provide a pressure roller which is independently adjustable at either end.

A further object of the invention is to provide a pressure roller which is adaptable to both minor and major variations in the surface of the printing cylinder or feed roller, whereby to be adjustable to operate in co-ordination with such variations.

Another object of the invention is to provide a double adjustment at each end of the pressure roller, whereby to maintain the same against the work sheet with the proper pressure and retain the roller from advancing beyond the proper limit.

An additional object of the invention is to design the novel pressure roller along simple and practical lines, whereby to be inexpensive to produce and adaptable to any printing press. With the above objects in view, and any others which may suggest themselves from the description to follow, a better understanding of the invention may be had by referring to the accompanying drawing, in which:

Fig. 1 is an elevation of a fragment of a printing press, showing the installation of the novel pressure roller; and

Fig. 2 is a plan view of Fig. 1;

Fig. 3 is a section on the line 3—3 in Fig. 1, partly in elevation.

Referring specifically to the drawing, it suffices for the present purposes that the sides of the printing press are represented at 10, the same having bearings 11 for the mounting of a feed roller 12. Beneath the latter is the novel pressure roller 13. The web or sheet is indicated by finely-dotted lines at 14, and it may be assumed that the roller 12 is driven to feed the web 14 with the frictional assistance of the pressure roller 13. Similarly, a large unit such as a printing cylinder may be substituted for the feed roller 12 and designed to print from a form 50 on its surface upon the web 14 and with the pressure roller 13 maintaining the latter in proper contact with the printing cylinder. Since the function of the pressure roller is the same in either case, its description in relation to the feed roller 12 will be a sufficient representation.

Referring to the pressure roller 13, it is seen that each terminal portion of its shaft 15 projects into a bushing 16 seated in a bearing 17, the latter being extended lengthwise under the roller in the form of a carrier 18. This carrier is intended to be vertically movable relative to a cross-bar 19 similarly positioned under the same and secured endwise to the sides 10 of the press, whereby to be in a stationary position. Fig. 3 shows the under side of the end of the carrier 18 slightly recessed at 18a to receive the upper end of an expansive spring 20 carried by a pin 21 which seats on one end portion of the cross-bar 19. A screw reduction 21a of the pin 21 threads through the set portion to receive a lock-nut 22 and a terminal head 21b. Thus, by means of the adjusting screw the tension of the spring 20 may be varied to impart the proper degree of pressure to the roller 13 in the direction of the web, in order that the proper contact may be had by the same for the feeding or printing operation.

Accessory to the pressure device just described is an adjustable control featuring a vertical pin 23 whose upper end is screwed into the roller carrier 18 indicated at 23a, the pin depending freely through a bore 19a in the cross-bar 19 and issuing from the latter in threaded form to receive a washer 24 and a hand nut 25. Beyond the latter the pin receives an expansive spring 26 before it terminates with a washer 37 and a polygonal head 23b. It is seen that by means of the hand nut 25 the upward pressure of the roller 13 may be controlled to limit the rise of the roller to a required height, the spring 26 serving to check the nut 25 from rotating freely from vibration. This adjustment is important when it is considered that the printing cylinder or feed roller may have inequalities or low areas at one or the other end, and the pressure roller 13 is therefore withheld from advancing beyond the proper point in respect to such areas.

When the press is not in use, the pressure roller 13 is preferably kept spaced from the units above it, in order that no difficulty may be had in threading the web or paper sheet through the zone of passage. The retaining element at each end of the roller is a hook 27 which acts as a yoke upon an end pin 18b of the roller carrier 18. The hooks 27 occur next outside the sides 10 of the press and are mounted on a rock shaft 28 journaled in the same. At one end the rock shaft carries a lever 29. Thus, the latter may be swung to the left from the position indicated
